UNITED STATES PATENT OFFICE

GEORGE E. FICHTNER, OF BOONTON, NEW JERSEY

DESIGN FOR A STOCKING

Application filed September 25, 1931. Serial No. 41,226. Term of patent 7 years.

To all whom it may concern:

Be it known that I, GEORGE E. FICHTNER, a citizen of the United States, residing at Boonton, in the county of Morris and State of New Jersey, have invented a new, original, and ornamental Design for a Stocking, of which the following is a specification, reference being had to the accompanying drawing, forming a part thereof.

The figure is a side view of a stocking showing my new design.

The ornamentation or decoration appearing on the upper part or cuff of the stocking extends completely around the same in an entire band.

I claim:

The ornamental design for a stocking, as shown and described.

GEORGE E. FICHTNER.
